UNITED STATES PATENT OFFICE.

CHARLES L. McBRIDE, JR., OF TOLEDO, OHIO, ASSIGNOR TO THE C. L. McBRIDE MFG. COMPANY, OF TOLEDO, OHIO, A CORPORATION OF OHIO.

GLOVE.

Application filed May 5, 1924. Serial No. 711,050.

This invention relates to gloves.

This invention has utility when incorporated in fabric gloves provided with reinforced wear portions.

5 Referring to the drawings:

Fig. 1 is a view of the palm of a glove embodying the invention;

Fig. 2 is a view of the back of the glove of Fig. 1;

10 Fig. 3 is a blank of the palm facing of the glove of Fig. 1;

Fig. 4 is a view of the facing blank for portions of the thumb back;

15 Fig. 5 is a view of the facing blank for portions of the back of the second or middle finger;

Fig. 6 is a view of the facing blank for portions of the back of the third finger;

20 Fig. 7 is a view of the facing blank for the back of the little finger;

Fig. 8 is a view of the extension facing for the palm;

25 Fig. 9 is a view of the blank for the palm and fingers of the main glove, and may be considered as a fabric or lining portion;

Fig. 10 is a view of the blank for the thumb lining back;

Fig. 11 is a view of the fabric lining back blank for the second finger;

30 Fig. 12 is a view of the fabric lining back blank for the third finger;

Fig. 13 is a view of the fabric lining back blank for the little finger; and

Fig. 14 is a view of the gauntlet blank.

35 In building gloves from the blanks hereunder, fabric palm 1 as having thumb lining 2 is assembled with thumb lining 3 and thumb facing 4 by common seam 5 which may extend over the top of the thumb and

40 back to the wrist as a continuous seam. This assembly may be after seam 6 has united this facing 4 to the lining 3. This seam 5 connects inner thumb facing 7 to the thumb facing 4, and leaves the thumb back

45 wristward from the seam 6 as exposing a portion of the thumb lining 3.

Palm facing 8 has index finger inside fac- 50 ing 9 with index finger back facing 10 integral therewith. This facing 10 is as-

sembled with index finger lining portion 11 integral with the palm lining 1 by seam 12 approximately from point 13 adjacent the inner crotch of the index finger. Back lining 14 may have back facing 15 connected

55 thereto by seam 16 approximately from be-

tween points 17, 18, of the lining 14. Third finger back lining 19 may have mounted thereon third finger back facing 20 by seam 21 approximately between the inner crotch portions between the second and third fingers and the third and little fingers, as determined by points 21, 22, on the back finger blank 19.

Little finger back lining 23 has assembled therewith little finger back facing 24 by seam 25 from point 26 approximating the crotch between the third and little fingers. Seams 27, 28, 29, may assemble these finger back linings with the partial finger back facings and leave the glove as an open structure. From the tip of the index finger, seam 30 as a closing seam may start and go down between the first and second finger, up over the second finger, down between the second and third finger, up over the third finger, down between the third and little finger, up over the little finger, and down the edge of the little finger to terminate at the wrist portion end of the lining 23 as assembled with the palm lining 1 to the 80 palm facing 8.

Gauntlet blank 31 may have assembled therewith, by seam 32, palm extension fac- 85 ing 33. This extension and gauntlet are as-

sembled by seam 34 with the glove linings and facings, so that this extension 33 has its seam 32 approximately continuous from the seam 6 to the wristward termination of the seam 30. While between the fingers, the

fourchettes or back facings are brought in by the respective seams 12, 16, 21, 25, there is but a single closing seam as an upward seam between the fingers which is effective in uniting the front and rear linings, as well

as the front and rear facings. There is, ac- 90 cordingly, a minimum of any knotting or packing of fabric in the crotches between the fingers. Furthermore, as assembled, the seams 25, 21, 16, 12, 6, 32, approximate a continuous curved line from the outer edge

95 of the little finger just above the knuckles in the hand, across the back of the hand, down- ward along the rearward edge of the thumb mount wristward to follow the palm exten- sion across the front of the hand to a point 100 on the closing seam 30 wristward from the point of starting at the seam 25.

In practice, it is convenient to assemble the gauntlet and its facing extension 33 with the glove before closing such up so 110

that the seam 30 extends from the little finger wristward, not only to the gauntlet 31, as at the wristward portion of the lining 32, but by seam 35 as a continuation of the seam 30 which effects closing of the gauntlet also.

The configuration of the facings is such as to permit economy in the cutting of such from leather or other material in the mounting thereof on cotton duck or other fabric. This economy is not only in the cutting of the leather but in the ways of assembly and sewing. The seaming or stitching is a minimum. While the fourchettes serve really as finger backs approximately over the two lower knuckles of each of the fingers, as such they are efficient in resisting wear. The cut-out for the thumb facing back along the seam 6 is also a material saving in the facing material. The unfaced portion of the back provides a glove which gives for

the hand portions a flexibility which contributes to ease for the wearer, while the portions of the fingers and hand subject to wear are reinforced by the several facings. 25

What is claimed and it is desired to secure by United States Letters Patent is:

A gauntlet glove having a palm, fingers, thumb, back, and gauntlet, a facing for the palm, fingers, and a portion of the thumb 30 and gauntlet, a facing boundary contour seaming approximating a continuous curved line from the outer side of the little finger across the back of the glove to wristward near the side of the thumb, and thence over 35 the gauntlet to the side of the hand toward the wrist from the point of starting with a straight line therefrom to the point of starting.

In witness whereof I affix my signature.

CHARLES L. McBRIDE, JR.
